UNITED STATES PATENT OFFICE

WALTER EVERETT MOLINS AND ALBERT ALEXANDER STONE, OF LONDON, ENGLAND

CIGARETTE MACHINERY

Application filed July 8, 1929, Serial No. 376,736, and in Great Britain August 28, 1928.

This invention is for improvements in or relating to cigarette machinery, and more particularly to a device for severing an axially moving rod into lengths, and has for its object the provision of such a device wherein the cutting blade is always maintained at right angles to the axis of the cigarette rod and is moved during the cutting operation in the direction of the axis of the cigarette rod without imparting a reciprocating movement to any of the parts of the cutting device.

The present invention consists of a cutting device for severing an axially moving rod into lengths which comprises a shaft secured against axial displacement, a blade or blades operatively connected to said shaft at a fixed point along the length of the same in such a manner as to be revolvable about the axis of said shaft in a plane, which includes the said fixed point and is inclined to a plane normal to the axis of the moving rod and means operable to maintain each blade normal to the direction of the axis of the moving rod throughout the entire path of the blade.

Further, the present invention consists of a cutting device for severing an axially moving rod into lengths which comprises a shaft secured against axial displacement, a blade or blades operatively connected to a disc or the like carried by said shaft at a fixed point along the length of the same in such a manner that the plane of the disc or the like is maintained during rotation at a constant angle to the axis of the rod, and a plane normal to the axis of the rod, and means operable to maintain the blade or blades at right angles to the axis of the rod during the cutting operation.

The invention will be more particularly described with reference to the accompanying drawings, in which:—

Fig. 1 is a side elevation, partly in section, of one method of carrying the invention into effect.

Fig. 2 is an end elevation of Fig. 1 looking in the direction of the arrow "A", and

Fig. 3 is a sectional elevation of a modified

form of the apparatus illustrated in Figs. 1 and 2.

Referring to Figs. 1 and 2, the apparatus comprises a disc 1 secured to a shaft 2 at a fixed point along the length of the same. 55 The shaft 2 is carried in a bearing bracket 3, and is so mounted that the plane of the plate 1 is inclined to the axis of the cigarette 16.

Mounted co-axially with the disc 1 is a fixed pinion 4 attached to the spindle bearing bracket 3 and adapted to drive a second pinion 5 idly mounted upon the disc 1 and arranged to gear with a third pinion 6 carried upon a spindle 7 rotatably mounted near the outer edge of the disc 1. The spindle 7 is provided at the free end thereof with an extension piece or head 8 arranged at an angle to the axis of the spindle 7. The head is in the form of a circular disc and a sleeve 9 is rotatably mounted thereon, but the sleeve 9 is held in a stationary position relatively to the disc 1 by means of a fork 10 extending at right angles from the surface of the disc 1 and engaging with an extension 11 on the sleeve 9 which carries the roller 12. The sleeve 9 has a cutting blade 13 mounted thereon, the blade being clamped by a plate 14.

The knife 13 is of the usual sickle shape as shown in Fig. 2, and a counter-weight 15 is mounted at the opposite end of the plate 1 to balance the apparatus, just described.

The inclination of the head 8 of the spindle 7 is such that the plane of the knife 13 is at right angles to the axis of the cigarette rod 16, and owing to the arrangement of gearing, previously described, the cutting edge of the knife always points in the same direction throughout the entire revolution of the disc 1.

In addition to the above, the knife receives a lateral movement in the direction of the axis of the cigarette rod, and the angle of inclination of the spindle 2 is such that the speed of translation of the knife is equal to the axial speed of the cigarette rod.

Referring to the modified form illustrated in Fig. 3, the outer pinion 6 is replaced by a pinion 7, the spindle 18 of which is large enough to form a bearing for a spindle 19 100

which carries a blade 20. The bearing for the spindle 19 is formed at an angle in the spindle 18 of the pinion 17 and the angle is such that it compensates for the inclination 5 of the disc 1 so that the plane of the knife is at right angles to the cigarette rod.

The remaining details of this form of the device are identical with that previously described.

- 10 In a modified form of the device, a circular blade is used in place of the sickle shaped blade, previously described, and the circular blade is rotated by securing the knife carrier spindle to a pinion meshing with a large 15 fixed sun gear and dispensing with the extension on the knife clamp, which in the case of the fixed blade, engages with a forked element mounted on the disc. The spindle of the knife carrier is rotatable in an obliquely bored bush which is constructed and driven 20 in the manner shown in Fig. 3.

From the above description it will be observed that the cutting device which forms the subject matter of the present invention 25 comprises the principle disclosed in Fig. 7 of U. S. Patent No. 1,630,132, the difference being that instead of a parallel link mechanism being provided for maintaining the spindle which carries the cutting blade parallel to 30 the axis of the cigarette rod, the said spindle is arranged to extend through the disc and engage with a bearing formed in a gear mounted on the disc which maintains the said spindle parallel to the axis of the cigarette rod.

Thus it will be seen that according to the present invention the cutting blade is maintained at right angles to the axis of the cigarette rod during the rotation of the same 40 about the axis of the plate, and at the same time is moved in the direction of the axis of the cigarette rod at the axial speed of the rod during the cutting operation.

What we claim as our invention and desire to secure by Letters Patent is:—

1. In a cutting device for severing an axially moving rod, the combination with a rotatable shaft, said shaft being angularly disposed with respect to a plane normal to the 50 direction of movement of the rod, of a cutting blade, and means carried by said shaft for supporting said cutting blade for rotation with said shaft and for maintaining said blade in planes normal to the direction of movement of said rod, said means including an element rotatable about an axis parallel to the axis of said shaft and having a journal portion disposed parallel to the direction of movement of the rod for rotatably engaging 55 said blade, and mechanism for rotating said element at the speed of rotation of said shaft and in the reverse direction.

2. In a cutting device for severing an axially moving rod, the combination with a 60 rotatable shaft, said shaft being angularly disposed with respect to a plane normal to the direction of movement of the rod, of a cutting blade, and means carried by said shaft

disposed with respect to a plane normal to the direction of movement of the rod, of a cutting blade, and means carried by said shaft for supporting said cutting blade for rotation with said shaft and for maintaining 70 said blade in planes normal to the direction of movement of said rod, said means including an element rotatable about an axis parallel to the axis of said shaft and having a journal portion disposed parallel to the direction of movement of the rod for rotatably engaging said blade, and planetary gearing for rotating said element at the speed of rotation of said shaft and in the reverse direction. 75

3. In a cutting device for severing an axially moving rod, the combination with a rotatable shaft, said shaft being angularly disposed with respect to a plane normal to the direction of movement of the rod, of a cutting blade, and means carried by said shaft for supporting said cutting blade for rotation with said shaft and for maintaining 80 said blade in planes normal to the direction of movement of said rod, said means including an arm supported on said shaft, an element carried by said arm for rotation about an axis parallel to the axis of the shaft, said element having a journal portion disposed parallel to the direction of movement of the rod for rotatably engaging said blade, and mechanism for rotating said element at the speed of rotation of said shaft and in the reverse direction. 85

4. In a cutting device for severing an axially moving rod, the combination with a rotatable shaft, said shaft being angularly disposed with respect to a plane normal to the direction of movement of the rod, of a cutting blade, and means carried by said shaft for supporting said cutting blade for rotation with said shaft and for maintaining 90 said blade in planes normal to the direction of movement of said rod, said means including an arm supported on said shaft, an eccentric bushing journaled in said arm, a stud carrying said blade and journaled in said bushing, and means for rotating said bushing. 95

5. In a cutting device for severing an axially moving rod, the combination with a rotatable shaft, said shaft being angularly disposed with respect to a plane normal to the direction of movement of the rod, of a cutting blade, an arm carried by said shaft and constituting the sole support for said blade, and means for maintaining said blade in planes normal to the direction of movement of the rod when said shaft is rotated. 105

6. In a cutting device for severing an axially moving rod, the combination with a rotatable shaft, said shaft being angularly disposed with respect to a plane normal to the direction of movement of the rod, of a cutting blade, and means carried by said shaft 110

for supporting said cutting blade for rotation with said shaft and for maintaining said blade in planes normal to the direction of movement of said rod, said means including
5 an arm supported on said shaft, an element carried by said arm for rotation about an axis parallel to the axis of the shaft, said element having a journal portion disposed parallel to the direction of movement of the
10 rod for rotatably engaging said blade, mechanism for rotating said element at the speed of rotation of said shaft and in the reverse direction, said mechanism comprising a fixed gear, a gear carried by said element, and a
15 gear meshing with both of said gears and carried by said arm.

In testimony whereof we hereunto affix our signatures.

WALTER EVERETT MOLINS.
